UNITED STATES PATENT OFFICE.

ARCHIBALD FERGUSON REDDIE, OF PHILADELPHIA, PENNSYLVANIA,
ASSIGNOR TO McCALLUM & McCALLUM, OF SAME PLACE.

DESIGN FOR CARPET.

SPECIFICATION forming part of Design No. 24,414, dated June 18, 1895.

Application filed March 4, 1895. Serial No. 540,532. Term of patent 3½ years.

To all whom it may concern:

Be it known that I, ARCHIBALD FERGUSON REDDIE, a citizen of the United States, residing at the city of Philadelphia, in the county 5 of Philadelphia and State of Pennsylvania, have invented and produced a new and original Design for a Carpet or other Fabric, of which the following, taken in connection with the accompanying drawing, is a specification.

10 My design is illustrated in the accompanying drawing in which—
a is the body, *b* is the border, and *a* and *b* a complete carpet.

15 Observers of the accompanying drawing will readily understand that which I desire to protect by Letters Patent and that which imparts a peculiar or distinctive appearance to the carpet to which it is applied.

20 Obviously my design may be applied to or wrought in velvet, Brussels, Wilton and other carpet fabrics and presented in various colors or shades or tints of colors and when so applied serves to distinguish such articles from others of like class and causes them to embody my invention.

The leading or characteristic feature of my design may be said to be striped scrolls, as *c*, contrasted with solid scrolls, as *d*, and diamond shaped ornamentations *e*, and the flowers *f*, and in the drawing, associated with 30 bands *g* and *h*.

What I claim as new, and desire to secure by Letters Patent, is—

1. In the design for a carpet the body *a*, substantially as shown.

2. In a design for a carpet the border *b*, substantially as shown.

3. The design for a carpet consisting of the body *a*, and the border *b*, substantially as shown.

40 In testimony whereof I have hereunto signed my name in the presence of two witnesses.

ARCHIBALD FERGUSON REDDIE.

Witnesses:

ANNA K. MAY,
HARRY O. SWEARER.
